TUFTED AND KNOTTED MATERIAL

Cosmo Caruso, Brooklyn, and David Rich,
Bronx, N. Y.

Application November 10, 1943, Serial No. 509,738

4 Claims. (Cl. 28—78)

This invention relates to new and useful improvements in a tufted and knotted material.

More specifically, the invention proposes the construction of a tufted and knotted material, which may be lined if desired, to be used for ladies' handbags and other objects and articles of a similar nature, and which is characterized by a sheet of facing material having rope-like strands disposed against the back face thereof in a manner to press outwards substantially tubular portions thereof so that the facing material forms the covering portions for the strands.

Another object of the invention proposes the provision of tuft-like strands at spaced positions along and engaging around the projecting tubular portions and passing through apertures in the facing material to be tied at the back face of the facing material in a manner to hold the facing material in position about the rope-like strands.

It is a further object of this invention to form a tufted and knotted material which is simple and durable which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a zipper type lady's handbag constructed of tufted and knotted material constructed in accordance with this invention.

Fig. 2 is an enlarged detail of a portion of Fig. 1.

Fig. 3 is a partial plan view looking in the direction of the line 3—3 of Fig. 2.

Fig. 4 is a horizontal sectional view taken on the line 4—4 of Fig. 2.

Fig. 5 is a rear perspective view of a portion of the tufted and knotted material before the ends of the tuft-like strands have been tied together.

The tufted and knotted material, according to this invention, includes a sheet of facing material 10 having rope-like strands 11 disposed adjacent the back face thereof. These strands 11 are preferably extended parallel to each other and spaced equally from each other. The strands 11 press outwards substantial tubular portions 12 of the facing material 10, and these tubular portions 12 act as covering portions for the strands 11.

Tuft-like strands 13 are arranged at spaced

positions along the length of each of the rope-like strands 11. These tuft-like strands 13 are engaged around the projecting tubular portions 12 and have their end portions passing through apertures 14 formed in the facing material 10 at the sides of the tubular portions 12. The ends of the tuft-like strands 13 after being passed through the apertures 14 are tied together at the back of the facing material 10, holding the tubular portions 12 of the facing sheet in position about the rope-like strands 11.

As shown in Fig. 2, the ends of the rope-like strands do not extend completely to the edge of the sheet of facing material 10, and the ends of the projecting tubular portions 12 are closed by a line of stitches 15 extended along the edges of the sheet of facing material 10.

In Fig. 1, a piece of tufted and knotted material constructed in accordance with this invention is illustrated made into a lady's handbag 20. However, this is merely by illustration, and it is to be understood that the material may be used equally as well for other objects and articles, such as: a bed spread, pillow or the like.

While we have illustrated and described the preferred embodiments of our invention, it is to be understood that we do not limit ourselves to the precise constructions herein disclosed and the right is reserved to all changes and modifications coming with the scope of the invention as defined in the appended claims.

Having thus described our invention, what we claim as new, and desire to secure by United States Letters Patent is:

1. A tufted and knotted material, comprising a sheet of facing material, rope-like strands disposed against the back face of said facing material and pressing outwards substantially tubular portions of said facing material which forms covering portions for said strands, and tuft-like strands at spaced positions along and engaging around said projecting tubular portions and having their end portions passing through apertures in said facing material and being tied at the back of said facing material.

2. A tufted and knotted material, comprising a sheet of facing material, rope-like strands disposed against the back face of said facing material and pressing outwards substantially tubular portions of said facing material which forms covering portions for said strands, and tuft-like strands at spaced positions along and engaging around said projecting tubular portions and having their end portions passing through apertures in said facing material and being tied at the back

of said facing material, said rope-like strands having their ends at some distance from the edges of said sheet of facing material, and means closing the ends of said tubular portions at the edges of said facing material.

3. A tufted and knotted material, comprising a sheet of facing material, rope-like strands disposed against the back face of said facing material and pressing outwards substantially tubular portions of said facing material which forms covering portions for said strands, and tuft-like strands at spaced positions along and engaging around said projecting tubular portions and having their end portions passing through apertures in said facing material and being tied at the back of said facing material, said rope-like strands having their ends at some distance from the edges of said sheet of facing material, and means closing the ends of said tubular portions at the edges

of said facing material, comprising stitches engaged through said facing material at the edges thereof.

4. A tufted and knotted material, comprising a sheet of facing material, rope-like strands disposed against the back face of said facing material and pressing outwards substantially tubular portions of said facing material which forms covering portions for said strands, and tuft-like strands at spaced positions along and engaging around said projecting tubular portions and having their end portions passing through apertures in said facing material and being tied at the back of said facing material, said rope-like strands being preferably arranged parallel to each other and spaced equally from each other.
